UNITED STATES PATENT OFFICE.

ANDREW J. CONNELL, OF COLLEGE POINT, NEW YORK, ASSIGNOR TO EMPIRE ART METAL CO., INC., A CORPORATION OF NEW YORK.

DOOR AND LIKE METALLIC STRUCTURE.

1,203,311.

Specification of Letters Patent.

Patented Oct. 31, 1916

Application filed January 12, 1914. Serial No. 811,784.

To all whom it may concern:

Be it known that I, ANDREW J. CONNELL, a citizen of the United States, and a resident of College Point, New York, have invented certain new and useful Improvements in Doors and like Metallic Structures, of which the following is a specification.

This invention relates to improvements in doors and like metallic structures.

By the use of my invention I produce a structure such as a door which will have a minimum number of parts; will take a fewer number of press operations to place such 15 parts in condition to be assembled, which assembling of parts may be done with great ease and rapidity and may be readily accomplished by unskilled labor; will have greater strength and rigidity when assembled than any structure heretofore made of like material and weight; the abutting portions of the parts may be readily and quickly welded and all the seams will be in condition to permit the ready and quick 20 sealing thereof by welding.

In the preferred embodiment of my invention illustrated in the accompanying drawings, each stile or rail member is formed of two parallel spaced side plates of sheet 30 metal, the opposing longitudinal edges of such plates, where such edges contact with the edges of an abutting member, being provided with inwardly-extending flanges bent at right angles to the side plates, and the 35 contacting edges of abutting members, such as the molding panel brackets and the transverse edges of the top, bottom and intermediate rails, are formed with a slot extending in the same direction as the aforesaid 40 flanges on the longitudinal edges of the stiles and rails, which slot is of substantially the same conformation as the flange and fits snugly over the same so as to form a seat therefor and such abutting members 45 are also preferably provided with a vertically extending portion adapted to abut against the inner sides of the stile or rail members and another portion extending inwardly at right angles to the aforesaid vertical portion, whereby a seat is provided by 50 means of the inwardly-extending flanges on opposite sides for a channel bracing bar, which bracing bar spans the space between the side plates of the stile or rail member 55 and abuts at opposite edges against the bot-

tom side of said slot and the abutting portion integral therewith so as to form a rectangular brace for the opposite sides of the stiles, the inwardly-extending flanges serving to retain such channel bars in position 60 preparatory to the welding of the same in place.

In the accompanying drawings, in which similar reference characters designate corresponding parts throughout the several views, Figure 1 is a side elevation of a door embodying my invention; Fig. 2 is a section on the line 2—2 of Fig. 1; Fig. 3 is a section on the line 3—3 of Fig. 1; Fig. 4 is a section on the line 4—4 of Fig. 1; Fig. 5 is a section on the line 5—5 of Fig. 1; Fig. 6 is a section on the line 6—6 of Fig. 1, showing the preferred method of closing the ends of the stile members; Figs. 7, 8 and 9 are respectively perspective views of portions of the molding member, channel bar and stile bar before the same are assembled; Fig. 10 is a sectional view of a modified form of door embodying my invention; and Fig. 11 is another sectional view of another modified form of door embodying my invention.

Referring now to Figs. 1 to 9 inclusive of these drawings which for the purposes of illustration only, show my invention applied to a door, though it is adapted for use in metallic partitions and other metallic structures, 1 and 2 indicate the stiles of a door, 3 and 4 the top and bottom rails, 5 the center rail, 6 the panel brackets or molding members, 7 a metallic panel and 8 a glass panel. The stiles and rails, as illustrated, are each formed of parallel spaced side plates of sheet metal designated 9 and 10 respectively, the top and bottom rails and the stiles being preferably formed with integral edge plates 11 and open at one longitudinal edge so as to be substantially U-shaped in cross-section, as illustrated in Figs. 2, 3, 5, and 7 to 9. The center rail or rails comprise similar parallel arranged side plates 9 and 10, open at both longitudinal edges as illustrated in Fig. 4. Each of the parallel spaced plates of the stiles and top and bottom rails are provided along one longitudinal edge with flanges 9a—10a extending inwardly from such plates at right angles thereto, and the center rail is likewise provided at both longitudinal edges with similar flanges 9a—10a. The panel brackets 6 are formed with the usual panel seats intermediate their edges and 110

contiguous to the longitudinal edges of the panel brackets 6 and also contiguous to the transverse edges of the top, bottom and center rails 3, 4 and 5 respectively. the metal is bent to form grooves 15—15^a which form seats for the opposing inwardly extending flanges 9^a—10^a respectively. The extreme edges of such members are preferably bent to form L-shaped portions 16 and 17, the vertical legs 16^a—17^a of such L-shaped portions abutting against the opposing parallel arranged side-plates and the other legs 16^b—17^b extending inwardly therefrom at right angles thereto. The two oppositely disposed L-shaped portions form a seat for a bracing or bridging channel 18, the flanges 18^a—18^b of which channel abut against the vertical legs of the L-shaped portions so as to permit ready welding of such bracing channel in place, the inwardly extending legs 16^b—17^b serving to retain the channel bar in place during assembling and to force the rectangular portions formed between the web and flanges into contact with the rectangular portions formed by the bottoms of the grooves and the vertical legs 16^a—17^a of the L-shaped portions. The parallel side plates of the stiles are left slightly longer than the finished height of the door or other structure and are bent inwardly to close the ends of such stiles as illustrated in Fig. 6 the two parts being then acetylene welded to close the seam, and I also preferably acetylene weld seams between the flanges 9^a—10^a and the grooved portions 15—15^a, thus forming a seamless door.

Obviously this door may be readily assembled by simply slipping the channel bars 18 in place within their seats along the longitudinal edges of the panel brackets abutting the top, bottom and center rails, which rails may be then readily applied by separating the flanges a sufficient distance to spring into the slots 15—15^a, whereupon the same may be electrically welded in place. The stiles may be then applied in a similar manner and the channels slid in place before closing up the ends as above described, whereupon the stiles may be spot welded through the vertical legs 16^a—17^a of the L-shaped portion 16 and the flanges 18^a—18^b of the bracing channel 18, after which the ends are closed and the seams sealed as above described.

In Figs. 10 and 11 I have illustrated slightly modified forms of my invention, Fig. 10 illustrating an L-shaped marginal flange having one leg extending downwardly and Fig. 11 illustrating similar L-shaped flanges with one leg extending upwardly, in each case the groove in the abutting member conforming to the shape of the flange. In other respects the construction is similar to that above described. In assembling the structures illustrated in Figs.

10 and 11, however, it will be necessary to slide the various parts together, instead of simply separating the flanges and permitting the same to spring within the slots as above described.

70

Having described my invention I claim:

1. A hollow sheet metal structure embodying inner and outer interconnected members, the inner member being provided with oppositely-disposed side walls each wall being bent intermediate its top and bottom to form an intermediate inwardly-extending groove, the mouth of which communicates with the outer side of said member, and to provide side wall portions at opposite sides of said groove; an outer member also having oppositely-disposed side walls extending parallel to the side walls of the inner member, each wall being provided with an inwardly-extending marginal flange adapted to seat within said intermediate groove, whereby a direct contact between the inner surface of the oppositely-disposed side walls of the outer member and the outer surface of the oppositely-disposed side walls of the inner member is provided.

80

2. A hollow sheet metal structure embodying inner and outer interconnected members, the inner member being provided with oppositely disposed side walls each wall being bent intermediate its top and bottom at a right angle to the plane of the said wall to form an intermediate inwardly-extending groove, the mouth of which communicates with the outer side of said member and also to provide side-wall portions at opposite sides of said groove extending in substantially the same plane; the outer member having oppositely disposed side walls extending parallel to and contacting with the side walls of the inner member, each wall of said outer member being provided with a marginal flange extending at a right angle to the plane of such walls and adapted to seat within said intermediate groove, and a stiffening member bridging said oppositely-disposed side walls and having flanges at opposite sides extending parallel with and abutting against the inner surfaces of the walls of the said inner member.

90

3. A hollow sheet metal structure embodying inner and outer interconnected members, the inner member being provided with oppositely-disposed side walls each wall being bent intermediate its top and bottom at a right angle to the plane of the said wall to form an intermediate inwardly-extending groove, the mouth of which communicates with the outer side of said member, and also to provide side-wall portions at opposite sides of said groove extending in substantially the same plane, each of said walls furthermore having at its free edge an inwardly-extending marginal flange; the outer member having oppositely-disposed side

walls extending parallel to and contacting with the side walls of the inner member, each wall of said outer member being provided with a marginal flange extending at 5 a right angle to the plane of such walls and adapted to seat within said intermediate groove, and a stiffening member bridging said oppositely-disposed side walls and having flanges at opposite sides extending par-

allel with and abutting against the inner surfaces of the walls of the said inner member.

In witness whereof, I have signed my name to the foregoing specification in the presence of two subscribing witnesses.

ANDREW J. CONNELL.
